Primary Examiner — Austin Murphy(74) *Attorney, Agent, or Firm* — Wissing Miller LLP(57) **CLAIM**

The ornamental design for a handle for in-line power tools, as shown and described.

DESCRIPTION

FIG. 1 is a front, first side perspective view of the new design for a handle for in-line power tools in accordance with the present invention;

FIG. 2 is a side elevation view of the first side of the handle for in-line power tools shown in FIG. 1;

FIG. 3 is a side elevation view of a second side of the handle for in-line power tools shown in FIG. 1;

FIG. 4 is a top plan view of the handle for in-line power tools shown in FIG. 1;

FIG. 5 is a bottom plan view of the handle for in-line power tools shown in FIG. 1;

FIG. 6 is a front elevational view of the handle for in-line power tools shown in FIG. 1; and,

FIG. 7 is a rear elevational view of the handle for in-line power tools shown in FIG. 1.

The broken lines within the various embodiments of the claimed design and the spaces therein are for environmental purposes only and form no part of the claimed design.
